UNITED STATES PATENT OFFICE.

MATHIAS LEONARD BROCHHAUSEN, OF ALBANY, NEW YORK.

FARM GATE.

Application filed August 16, 1927. Serial No. 213,230.

This invention relates to self-opening farm gates of the kind which are adapted to open automatically when a vehicle approaches the gate and to close automatically when the vehicle has passed through the gate.

The invention has for one of its objects a centrally pivoted gate which may be caused to open and remain open automatically when a vehicle wheel is in a predetermined area of the roadway and to close automatically when the vehicle wheel leaves such area. To this end, one arm of a lever pivoted beneath the gate is adapted to be depressed by a track with which a wheel of a vehicle contacts, thereby elevating the other arm of the lever which causes the elevation of a pivot upon which the gate is carried. Cam surfaces are provided to cause the swinging of the gate about the pivot on an arc of a circle and the gate is caused to remain in open position at right angles to its normally closed position so long as the vehicle wheel contacts with the track by cooperating surfaces on the gate and its pivot. The gate is closed by instrumentalities affected by the weight of the gate when not overbalanced by the weight of a vehicle on the track.

A further object of the invention is the retention of the gate in closed position by locking devices which will be automatically released when the vehicle wheel passes onto the track. Accordingly, devices on the gate and on a relatively stationary portion of the structure are adapted to interengage when the gate is in closed position, but to disengage when the gate pivot is raised by the said levers preparatory to effecting the rotation of the gate to open position.

A further object of the invention is the provision of means for manually opening a portion of the gate to permit a pedestrian to pass. To this end a portion of the gate is hinged with respect to the remainder of the gate and manually releasable devices are provided to normally maintain the hinged portion in rigid relation with the remainder of the gate.

The invention also seeks a gate structure and gate operating means which shall be practical from the standpoint of ease and cheapness of manufacture and durability and convenience in use.

These and other objects of the invention and the means for their attainment will be more apparent from the following detailed description taken in connection with the ac-

companying drawings illustrating a preferred embodiment thereof, in which:

Figure 1 is a view in front elevation and partly in section showing the gate according to this invention and the operating mechanism therefor.

Figure 2 is a plan view of the structure illustrated in Figure 1.

Figure 3 is a fragmentary view in side elevation of the gate pivot and gate rotating mechanism in gate closed position, parts being removed in the interest of clearness.

Figure 4 is a section on the line 4—4 of Figure 3.

Figure 5 is a view in front elevation and partly in section on the line 5—5 of Figure 3.

Figure 6 is a front elevational view similar to Figure 3 but showing the mechanism when the gate is in open position.

Figure 7 is a side elevational view of the mechanism in the position shown in Figure 6.

Figure 8 is a view similar to Figure 3 but showing a modification of the invention in which means are provided for locking the gate in closed position.

Figure 9 is a view, partly in section, on the line 9—9 of Figure 8.

An opening 11 in a fence 12 adapted to be closed by a gate 13 according to this invention is shown in Figures 1 and 2. Beneath the surface of the roadway 14, between the gate posts 15, and in prolongation of the fence 12, that is, transverse to the roadway 14, there is disposed a pair of channels 16, 16, of any suitable material, preferably sufficiently below the surface of the roadway to permit the concealment of all parts of the gate actuating mechanism below the road surface 14. These channels 16 form between them a slot or space 17 for transversely extending operating levers 18, which are pivoted as at 19 to the channels 16 and are so disposed that the ends 20 of the longer arms are proximate one another at the center of the roadway, while the ends 21 of the shorter arms are at the sides of the roadway 14 and may extend slightly above the upper webs of the channels 16.

Extending in opposite directions adjacent the margins of the roadway 14 are runways or tracks 23 for the "off" wheel or wheels of a conveyance, not shown. These tracks 23 extend, one on each side of the road, in a direction opposite to that in which the gate 13 swings horizontally about its midpoint so that a wheel of a vehicle approaching the

gate and keeping to the right will ride up on to the track and depress it. The outer end of the track 23 rests on the surface of roadway 14 while the track terminates proximate the 5 gate and rests, in elevated position, upon a plunger 24. This plunger 24 may take the form of a section of an I beam, reciprocating in a guide 25, within which the end of the track also is guided. When the end of the 10 track 23 is depressed by the weight of a vehicle, the plunger 24 depresses the end 21 of lever 18 and thereby elevates end 20 at the center of the roadway. It is the elevation of this end and the contacting thereof with gate 15 rotating mechanism which effects the opening of the gate.

At its midpoint the gate 13 is formed with a tubular pivot bearing member 27 which reciprocates on and rotates upon a central pivot 20 28 (Figure 3). Pivot 28 and tubular bearing member 27 extend below the surface of the roadway into a chamber or space 22 between a surface plate 14' and the top flanges 33 of the channels. At its lower end the 25 gate tube 27 is formed with or is carried on a wedge shaped cam 29 which rests on and rotates on a cam surface formed on a cylindrical base cam 30. Cam 30 is preferably formed with a flange 31 by which it may be secured, as by the bolts 32, to the top flanges 33 of the channels 16.

The pivot 28 terminates in a lever bearing member 34 which is preferably rectangular in cross section and is formed at its lower end 35 with a rectangular plate slightly larger in its transverse dimensions than the member 34 and which serves as the bearing with which the lever ends 20 engage and by which the pivot 28 is raised.

40 Centrally the channels 16 are slotted vertically, as at 36, to receive the squared lever bearing member 34, 35 of the central pivot member 28. The upper end or top of this lever bearing member 34, 35 is angularly notched, as at 37 on a diagonal thereof and in a direction transverse to the plane of the channels 16 as shown clearly in Figures 5 and 6. This notched top surface may be considered as a movable camming surface.

50 The cam base 30 is formed with four cam surfaces 40, 41, 42 and 43 comprising oppositely disposed elevated points or dwells 46 and 47 defined by the descending cam surfaces 41 and 43 and the ascending cam surfaces 40 and 42, respectively.

The elevated points 44 and 45 are diagonally opposite one another and lie in a vertical plane A—A through the vertical axis of the pivot but at an angle to the vertical plane 60 B—B transverse to the channels 16 and to the plane including the V-shaped notch 37 (see Figure 4). Considering the desired direction of rotation of the gate as counterclockwise, as viewed from above, in order 65 that its end may rotate away from an ap-

proaching vehicle, the vertical plane including the high points lies at an angle to the plane of the V slot 37 which lags behind the transverse plane, that is, it is at an angle described in a clockwise direction from that 70 plane, when viewed from above.

The low points 46, 47 are similarly in a vertical plane C—C but at an angle in advance or counterclockwise of the median plane D—D of the channels 16. 75

The gate 13 is so mounted on the bearing tube 27 as to lie in the longitudinal plane D—D when the tracks 23 are not depressed. In this situation, of course, the bearing 34, 35, due to its own weight and to the weight 80 of the gate, is at the lowermost point, thereby depressing the ends of the levers and permitting the lowering of the wedge which strikes the cam surfaces in the plane B—B and is directed downwardly down the inclined cam 85 surfaces 41 and 43 to come to rest finally in the low points 46 and 47. At this time high points of the V slot 37 are below the lowest edge 29' of the wedge 29 as shown in Figure 5.

When now the gate is to be opened by an approaching vehicle, the vehicle, keeping to the right of roadway 14, is so directed that its off wheel or wheels contacts with the track 23 and the weight of the vehicle causes a depression of the plunger 24 and end 21 of lever 90 18 and thereby an elevation of end 20 of the lever 18. This elevation of end 20 raises the bearing member 34, 35 so that diagonally opposite side edges of the V slot 37 contact with the edge of the wedge 29 and raise the 95 same. The tendency of the wedge to slide down the edge of the V slot is opposed by the ascending cams 40 and 42 and as the V slot continues to rise the travel of the wedge 100 against the cam surface 40 and 42 causes said cam to rotate until it rests in the V slot and the edge of the cam and hence the plane of the gate lies in the transverse plane B—B in the median line of the roadway. This rotation 105 of the wedge obviously carries the gate with it on the arc of a circle.

When the vehicle wheel passes off the track and no further weight is placed on the end 21 of lever 18 the weight of the gate lowers the pivot bearing member 34, 35 so 110 that the wedge 29 is again permitted to contact with the cam base 30. This contact occurs on the line B—B (Figure 4) on the descending cam surfaces 41 and 43 and as the wedge edge 29' rides thereover to rest in the 115 low points 44 and 45 the gate is swung to closed position, Figure 5.

Obviously, it is desirable to lock the gate in closed position to prevent accidental opening, as by an animal pushing against the gate. 120 To this end the wedge 29 may be formed with a downwardly extending lug 50 in prolongation of the edge 29'. This lug 50 is adapted to fit into a recess 51 formed at the low point or points 46 and/or 47 of the cam surfaces 125 130

so that when the gate is in closed position the lugs in the recesses prevent rotation of the gate to open or partially open position except when the tubular bearing member 27 is 5 raised through the instrumentalities of the pivot 28 and tracks 23.

It is also proposed according to this invention to provide for the passage of a pedestrian through the gate without necessitating the use of the gate rotating mechanism. 10 Accordingly, one or both wings 13' of the gate are pivotally or hingedly mounted on the pivot bearing tube 27 as at 53 and, preferably, at the top the wing is provided with 15 an arm 54 releasably secured, as by the pin 55, to an apertured lug 56 carried with the tube 27. When the arm 54 is joined to the lug 56 by the pin 55 the gate wing is rigid with the rest of the gate structure and swings 20 therewith. When the pin 55 is manually removed the wing 13' may be swung open about its hinge 53 with respect to the remainder of the gate as shown in dotted lines in Figure 2 to permit the passage of a pedestrian 25 or a led animal therethrough.

It will thus be seen that a farm gate has been provided which is adapted to be automatically opened when a vehicle approaches the same over a specified area and which will 30 automatically close after the vehicle has passed therethrough. If desired, the gate may be so constructed as to effect an automatic latching and unlatching of the gate in closed position. By a simple manually operable device the gate may be opened, at least 35 in part, for the passage of a pedestrian.

Various modifications will occur to those skilled in the art in the composition and configuration of the component elements by 40 which this farm gate is shown to be realized and no limitation is intended by the phraseology of the foregoing description or illustrations in the accompanying drawings except as set forth in the appended claims.

45 What I claim is:

1. A farm gate comprising, in combination, a centrally pivoted gate and means to cause said gate to open including a track adjacent an edge of the roadway, a lever pivoted below the surface of the roadway and having one end beneath the track and its other end beneath the gate pivot, and means to close the gate dependent upon the weight thereof.

55 2. A farm gate comprising, in combination, a tubular pivot bearing carried with the gate, a pivot upon which the bearing reciprocates and rotates, a wedge carried with the bearing, a circular cam with which the wedge 60 engages and means to elevate the wedge including a track upon which at least a portion of a vehicle rests and a lever engaging the track.

65 3. A farm gate comprising, in combination, a tubular pivot bearing carried with the gate,

a pivot upon which the bearing reciprocates and rotates, a wedge carried with the bearing, a circular cam with which the wedge engages and means to elevate the wedge, including a movable camming surface carried 70 with the pivot to engage the wedge.

4. A farm gate comprising, in combination, a tubular pivot bearing carried with the gate, a pivot upon which the bearing reciprocates and rotates, a wedge carried with 75 the bearing, a circular cam with which the wedge engages and means to elevate the wedge, including a movable camming surface, a lever pivoted beneath the roadway having one end adapted to elevate the movable camming surface and the other end adapted to be depressed by a vehicle carried with the pivot to engage the wedge.

5. A farm gate, comprising, in combination, a tubular pivot bearing carried with the gate, a pivot upon which the bearing reciprocates and rotates, a wedge carried with the bearing, a circular cam with which the wedge engages, and formed with diametrically opposite high points and diametrically opposite 90 low points angularly disposed with respect to the gate, and means to elevate the wedge, including a movable camming surface carried with the pivot to engage the wedge and having diametrically opposite low points in a 95 plane normal to the gate.

6. A farm gate comprising, in combination, a tubular pivot bearing carried with the gate, a pivot upon which the bearing reciprocates and rotates, a wedge carried with the bearing, 100 a circular cam with which the wedge engages and means to elevate the wedge, including a movable camming surface carried with the pivot to engage the wedge and means to prevent rotation of the movable cam.

7. A farm gate comprising, in combination, a centrally pivoted gate, transverse channels defining a lever operating space below the road surface, each formed centrally with a cut away slot, a transversely extending lever 110 pivoted in the space, a plunger resting on the end of the lever, a track along the edge of the road resting at one end in elevated condition on the plunger, a circular cam resting on the channels but beneath the road surface and formed with a vertical angular bore and with 115 diagonally opposite elevated dwells defined by a vertical plane angularly disposed with respect to a vertical plane normal to the gate

in closed position, and described in a direction of rotation away from the direction of opening of the gate and with diametrically opposite low spots disposed in a vertical plane angularly disposed with respect to a vertical plane including the gate in closed position 120 and described in the said direction of rotation of the gate, a pivot having a squared lower end disposed between the channels and reciprocating in the slots thereof and a tubular pivot bearing carried with the gate at its mid-

125

point and reciprocable and rotatable upon the pivot and formed at its lower end with a wedge adapted to rest on the circular cam.

8. A farm gate comprising, in combination, a centrally pivoted gate, a track along the edge of the road resting at one end in elevated position on one end of the lever, a circular cam formed with a vertical angular bore and with diagonally opposite elevated dwells disposed in a vertical plane angularly disposed with respect to a vertical plane normal to the gate in closed position, and described in a direction of rotation away from the direction of opening of the gate and with diametrically opposite low spots disposed in a vertical plane angularly disposed with respect to a vertical plane including the gate in closed position and described in the said direction of rotation of the gate, a pivot resting on the other end of the lever, a tubular pivot bearing member carried with the gate and having a wedge at its lower end resting on the circular cam.

9. A farm gate comprising, in combination, a tubular pivot bearing carried with the gate, a pivot upon which the bearing reciprocates and rotates, a wedge carried with the bearing, a circular cam with which the wedge engages, means to elevate the wedge, and means to lock the gate in closed position including a lug carried with the wedge adapted to enter a recess formed in the circular cam.

10. A farm gate comprising in combination a tubular pivot bearing carried with the gate, a pivot upon which the bearing reciprocates and rotates, a wedge carried with the bearing, a pair of similar cams set at right angles to each other, one of said cams being fixed and the other being movable, and means to elevate the wedge including the movable cam.

11. A farm gate comprising in combination a tubular pivot bearing carried with the gate, a pivot upon which the bearing reciprocates and rotates, a wedge carried with the bearing, a pair of similar cams set at right angles to each other, one of said cams being fixed and the other being movable, and means to elevate the wedge including the movable cam, a track in the roadway and a lever engaging the track and movable cam.

12. A farm gate comprising, in combination, a tubular pivot bearing carried with the gate, a pivot upon which the bearing reciprocates and rotates, operating members comprising a wedge carried with the bearing, and a circular cam with which the wedge engages, means to elevate the wedge, and means to lock the gate in closed position including a lug carried by one of the operating members and adapted to enter a recess formed in the other member.

In testimony whereof I affix my signature.
MATHIAS LEONARD BROCHHAUSEN.
